UNITED STATES PATENT OFFICE.

HERMAN E. SCHMIDT, OF RAPIDAN, MINNESOTA.

DRAFT-EQUALIZER.

SPECIFICATION forming part of Letters Patent No. 233,557, dated October 19, 1880.

Application filed March 15, 1880. (No model.)

To all whom it may concern:

Be it known that I, HERMAN E. SCHMIDT, of Rapidan, in the county of Blue Earth and State of Minnesota, have invented a new and 5 Improved Draft-Equalizer, of which the following is a specification.

The object of this invention is to provide a device to be attached to a vehicle for the purpose of equalizing the draft of three horses. 10 The invention consists of several bars or levers for carrying the double and single trees, arranged upon the tongue or pole of the vehicle in such a manner that the draft or pull of one horse on the long arm of the main lever 15 will equalize the draft or pull of two horses at the short arm thereof.

The drawing represents a plan of the device.

In the drawing, A represents the tongue or 20 pole of a vehicle. B is a long bar or lever, pivoted near one end to the face of the tongue A by spring and bolt *a*, or other convenient device. This lever B is usually made of wood, is about five feet long, and of the desired 25 strength.

C is a brace, preferably of iron, pivoted at one end on the face of the tongue A, near the rear end thereof, as shown at *b*, said brace C extending diagonally and laterally forward until 30 about on a horizontal line with the pivots of the bar or lever B, and then having its end turned at an obtuse angle, as shown at *d*, and extended parallel with the tongue A. Pivoted on this front end of the brace C is the 35 short bar or lever D, which extends inward a little more than half-way over the tongue A, and at right angles thereto. A clevis, *f*, connects the extreme end of the short arm of the lever B with this short lever D, near the pivoted end of said lever D, said clevis *f* serving

as a fulcrum to said lever. From the free end of the long arm of this lever D depends a clevis, *g*, that carries a double-tree, E, (shown in dotted lines,) from whose end clevises, *h h*, the single-trees F F (also shown in dotted lines) 45 may be suspended. This clevis *g* hangs centrally over the face of the tongue A, so that the double-tree E may extend equally on either side of the said tongue.

On the extreme end of the long arm of the 50 lever B is fixed a clevis, *m*, from which depends a single-tree, G, (shown in dotted lines.)

The brace C prevents an extreme rearward movement of the short arm of the lever D when horses are pulling at the double-tree E, 55 or at the single-trees F F, thereto attached, and consequently limits the rearward movement of the long arm of the lever B, while the pull of one horse on the long arm of said lever B, or on the single-tree G, thereto attached, is 60 calculated to hold said lever B at right angles to the tongue A against the pull or draft of two horses at the other end of said lever B.

One horse attached to the long arm of the lever B, or two horses attached to the lever D, 65 may draw the vehicle to which the tongue A is attached without disarranging the parts herein shown.

Having thus described my invention, I claim as new and desire to secure by Letters Patent—

A draft-equalizer constructed substantially as herein shown and described, consisting of the long lever B, brace C, and short lever D, with their respective clevises and pivots attached to the vehicle-tongue A, as set forth.

HERMAN E. SCHMIDT.
